DESIGN FOR A DRAWER PULL

Odin A. Westgaard, Los Angeles, Calif., assignor
to Modern Plastics Company, Los Angeles,
Calif., a corporation of California

Application October 20, 1939, Serial No. 87,751

Term of patent 7 years

To all whom it may concern:

Be it known that I, Odin A. Westgaard, a citizen of the United States, residing at Los Angeles, in the county of Los Angeles and State of California, have invented a new, original, and ornamental Design for a Drawer Pull, of which the following is a specification, reference being had to the accompanying drawing, forming part thereof.

Figure 1 is a view in side elevation of the

drawer pull embodying my new design; Fig. 2 is a view in front elevation of the same; Fig. 3 is a rear view in elevation of the same; and Fig. 4 is a view taken substantially upon the line 4—4 upon Fig. 1.

I claim:

The ornamental design for a drawer pull, as shown.

ODIN A. WESTGAARD.
